APPARATUS FOR USE IN THE INSTRUCTION OF SWIMMING

Cameron McDermott, Pewaukee, Wis.

Application November 2, 1933, Serial No. 696,301

1 Claim. (Cl. 272—71)

This invention relates to apparatus for use in the instruction of swimming, and has as an object to provide an apparatus by which the arms and legs are positively and coordinately moved as required in a particular swimming stroke.

More specifically, it is an object of this invention to provide an apparatus adapted to be set up in a gymnasium or in the home, and having a table like support on which the user lies with his legs and arms engaging movable elements adapted to positively move the arms and legs, as is necessary to perform correctly a certain style of swimming, especially the "crawl", although the motions of other strokes also may be produced.

With the above and other objects in view which will appear as the description proceeds, my invention resides in the novel construction, combination and arrangement of parts substantially as hereinafter described and more particularly defined by the appended claims, it being understood that such changes in the precise embodiment of the herein disclosed invention may be made as come within the scope of the claims.

In the accompanying drawings, I have illustrated one complete example of the physical embodiment of my invention constructed according to the best mode I have so far devised for the practical application of the principles thereof, and in which:

Figure 1 is a side view of the apparatus and illustrating its manner of use;

Figure 2 is a top plan view;

Figure 3 is a rear end view;

Figure 4 is a detail section view taken through Figure 1 on the plane of the line 4—4; and

Figure 5 is an enlarged fragmentary section view through one of the guide channels illustrating a structural detail.

Referring now more particularly to the accompanying drawings in which like numerals indicate like parts throughout the several views, the numeral 5 represents the general frame of the apparatus which is preferably formed of tubing and consists of two similar side units 6 connected together by upper and lower cross members 7 and 8, respectively.

Each side unit consists of a lower longitudinal rail 9 and a top rail 10, maintained in spaced parallel relationship by vertical members 11 and diagonal braces 12.

The various members are connected together by suitable fittings to which they are preferably welded and certain of the lower fittings are provided with feet 13, upon which the entire apparatus rests. It is observed that the vertical

members 11 have their medial portions bent outwardly to add to the space within the frame.

Extending across the lower side rails 9 are shelves 15, 16 and 17. Mounted on the cross shelves 15 and 16, respectively, are pedestals 18 and 19 which support a table indicated generally by the numeral 20. The table 20 comprises a stationary rear section 21 and a rocking forward section 22. The forward section 22 is mounted on a longitudinal supporting shaft 23, having its ends anchored to the upper ends of the pedestals 18 and 19.

The sections of the table are so proportioned that the rear fixed section 21 supports substantially the hips of the user, while the forward 15 rocking section 22, supports the chest and shoulders. It is observed that the front end of the rocking section 22 is inclined upwardly so as to insure arching of the back. The manner in which the rocking of the forward section is effected 20 will be hereinafter described.

Hingedly attached to the rear edge of the fixed table section 21 are two leg supports 24 of a length to extend substantially to the ankles. Spring clasps 25 at their outer free ends of these 25 supports engage and hold the ankles.

The leg supports 24 are supported and are simultaneously and oppositely reciprocated up and down by connecting rods 26 attached at their upper ends to the leg supports 24 as at 27 and 30 connected at their lower ends to eccentrics 28. The eccentrics 28 are fixed to a cross shaft 29 journalled in bearings 30 resting on the rear portion of the shelf 15.

Mounted on the inner face of each side unit 35 6 is a substantially elliptical channel track 31. As best illustrated in Figure 5, the channel tracks have their open inner sides partially closed by plates 32, the space left being sufficient to accommodate extensions 33, projecting inwardly 40 from the tracks and carried by endless sprocket chains 34 disposed therein.

The extensions 33 of the two chains are diametrically opposite, and attached to their outer ends are flexible connections 35 provided with 45 loops at their outer free ends to receive the hands or wrists of the user.

The sprocket chains are driven about the channel tracks in a clockwise direction with respect to Figure 1, by drive sprockets 36 located at the 50 forward end of the apparatus. Obviously, where the drive sprockets 36 mesh with the sprocket chains, the outer walls of the channel tracks are cut away to permit the sprocket wheels to enter and mesh with the chains.

Operation

The sprockets 36 are fixed to a cross shaft 37, journalled in bearings 38 mounted on the shelf 17 and driven from a motor 39 mounted on an extension of the shelf 17, through a belt drive 5 40. Inasmuch as both chains are driven from the single drive shaft 37, it follows that they are at all times in step with their hand engaging elements at all times opposite each other.

It is observed that the drive shaft 37 also drives 10 a longitudinal shaft 41 through a bevel gear connection 42. The longitudinal shaft 41 has its rear end journalled in a bearing carried by the pedestal 19 and its forward end journalled in a bearing 43 mounted on the shelf 17.

15 Adjacent the pedestal 19, the shaft 41 has a pinion 44, which meshes with a gear 45 fixed to a stub shaft 46 journalled in a bearing also carried by the pedestal 19. The opposite end of the stub shaft has a small crank disc or eccentric 20 driver 47 fixed thereto which is connected through a rod 48, with the rocking forward table section 22. The gear ratios of the pinion and gear 44 and 45 respectively, and the bevel gear connection 42, are such that the rocking of the table 25 section 22 is properly coordinated with the motion of the chains, which carry the arms of the user through their required movements.

At the rear end of the apparatus, there are 30 two power take-off sprockets 49, meshing with the sprocket chains. These sprockets are fixed to a cross shaft 50, journalled in bearings carried by levers 51 pivotally mounted on the shaft 29 adjacent its bearing supports 30. The shaft 50 also has a pinion 52 fixed thereto, which meshes 35 with a gear 53 fixed to the shaft 29, so that the shaft 29 is driven from the chains through the power take-off sprockets.

The levers 51 have extended end portions 54 40 provided with arcuate slots 55 concentric to the axis of the shaft 29. Locking screws 56 threaded in extensions of the bearing supports 30 and having their heads engaged in the enlarged end portions of the arcuate slots 55, serve to hold the levers 51 in either of two positions of adjustment.

45 Through this adjustability of the levers 51 which carry the shaft 50, it is possible to alter the ratio between the speed of the sprocket chains and the cross shaft 29, which actuates the leg supports. In the embodiment illustrated, the ratio is such that a six beat crawl stroke is produced.

Substituting power take-off sprockets of 55 smaller diameter for the sprockets 49 and adjusting the levers 51, accordingly, permits the ratio to be quickly changed to produce an eight beat stroke. Other ratios of the leg movements to the arm movements are possible with similar alterations.

As stated, the present embodiment is arranged for the instruction of the six beat crawl. In this stroke, there are six leg beats, three with each leg, to one complete cycle of arm movements. Also, for each cycle of arm movements, the upper part of the body rolls to one side, preferably the right, to permit taking in a breath of air. These movements are all positively coordinated in the 10 present apparatus. 5

The manner of use is clearly illustrated in Figure 1. As here shown, the user lies on his stomach, engages the ankles with the spring clasps 25, and inserts his hands through the loops of 15 the flexible connections 35. The motor is then started by an attendant, and the various movements take place.

It is, of course, obvious that the exact motion of the arms is not obtained through the functioning of the apparatus, but coordination of the arm and leg movements with the body roll are obtained, and this is the most difficult part of learning this particular stroke. 20

From the foregoing description, taken in connection with the accompanying drawings, it will be apparent to those skilled in the art that this invention provides novel means for facilitating the instruction of different strokes in swimming and while the embodiment illustrated shows its 30 adaptation particularly to that style of swimming known as the "crawl", it is readily apparent that the apparatus may be easily adapted for the instruction of the other styles of swimming especially the back stroke, without deviating from 35 the spirit of the invention. 25

What I claim as my invention is:

In an apparatus for the instruction of swimming, a substantially horizontal body support composed of a stationary portion and a rockable 40 portion, means to mount said body support including spaced pedestals one of which supports the fixed portion of the body support directly, means to rock the body support comprising a crank rotatably mounted from the other pedestal, 45 a rod connecting the crank and the body support, leg supports hinged to the fixed portion of the body support, crank means to reciprocate said leg supports, substantially elliptical guide tracks at opposite sides of the body support, means 50 travelling about said guide tracks to carry the arms along defined paths, and drive means to simultaneously actuate the cranks driving the rocking body support and the leg supports and to cause said arm carrying means to travel about 55 the guide tracks.

CAMERON McDERMOTT.
